UNITED STATES PATENT OFFICE

2,428,610

METHOD AND APPARATUS FOR MANUFACTURING ELECTRIC DISCHARGE DEVICES

James E. Beggs, Scotia, N. Y., assignor to General Electric Company, a corporation of New York

Application September 10, 1943, Serial No. 501,791

34 Claims. (Cl. 316—32)

1

My invention relates to electric discharge devices and, in particular, to methods and apparatus for manufacturing such devices.

It is an object of my invention to provide a new and improved method for manufacturing an electric discharge device.

It is another object of my invention to provide a new and improved apparatus for manufacturing electric discharge devices.

It is a further object of my invention to provide a new and improved method of manufacturing electric discharge devices in which the characteristics of the devices are established during the period while the devices are being evacuated.

It is still another object of my invention to provide a new and improved method of controlling the physical spacing of the electrodes of an electric discharge device.

It is a still further object of my invention to provide a new and improved apparatus for adjusting the electrical characteristic of an electric discharge device during the manufacture of that device.

It is another object of my invention to provide a new and improved method for manufacturing an electric discharge device in which, during the manufacture thereof, the electrical characteristics of the device are established under normal operating conditions.

A further object of my invention is to provide a new and improved method of sealing an electric discharge device.

Still another object of my invention is to provide an improved apparatus for controlling the physical spacing of the electrodes in an electric discharge device.

Another object of my invention is to provide improved method and apparatus for evacuating an electric discharge device.

Briefly stated, in accordance with one aspect of my invention, I provide new and improved methods and apparatus for constructing an electric discharge device in which, while the device is supported in an evacuated chamber, the electrical characteristics of the device are adjusted under normal operating conditions and while the device is hermetically but not mechanically sealed. Alternatively, in accordance with another aspect of my invention, physical spacing of any desired pair of electrodes of the device may be adjusted precisely while the device is being evacuated, at operating temperatures, and after the device has been hermetically sealed, but before all joints are made mechanically rigid. The final sealing of the electric discharge device is

2

accomplished within an evacuated chamber and means are provided external of the chamber for supplying operating potentials to the electrodes of the device and for making final adjustment of the position of an electrode of the device. To insure that the device will operate with desired electrical characteristics the output currents of the device are utilized to measure the spacing of the electrode whose position is being adjusted.

10 Means are also provided to seal hermetically the electrode to be adjusted in an approximate operating position, which means includes a molten metallic seal. A final gas pressure within the sealed device is obtained while the device is being evacuated and after the molten metallic seal has been formed.

For a better understanding of my invention, reference may be had to the following description taken in connection with the accompanying drawing and its scope will be pointed out in the appended claims. Fig. 1 of the drawing is an elevational view of a section of apparatus for manufacturing an electric discharge device in accordance with my invention; and Fig. 2 illustrates an alternative electric circuit which may be employed with the apparatus of Fig. 1.

In Fig. 1 of the drawing, my invention is there shown as embodied in apparatus comprising an electric discharge device 1 to be exhausted and hermetically sealed, an enclosed chamber 2 which is evacuated by means of a vacuum pump 3, and apparatus 4 for adjusting the position of the cathode of the electric discharge device 1 during the period that the device is being exhausted.

30 The discharge device 1 is described and claimed in my copending application, Serial No. 501,790, filed September 10, 1943, and assigned to the assignee of this application.

Electric discharge device 1 comprises a cylindrical anode 10, a composite cylindrical cathode structure 11, and may include a pair of control electrodes or grids 12, 13. Concentrically surrounding the cylindrical anode 10 is a metallic sleeve 14 having inwardly and outwardly directed flanges at its opposite ends. Hermetically sealed between the anode 10 and the inwardly directed flange of sleeve 14 at a point spaced longitudinally from the electron receiving surface of the anode is a disk 15 constituted of a material having a thermal coefficient of expansion substantially equal to that of the metallic members to which it is connected and also, preferably, having a low dielectric loss at high frequencies. Concentrically surrounding the composite cathode structure 11 is a hollow metal cylinder 17. A metal

sleeve 18, similar to the metallic sleeve 14, is concentrically aligned with the hollow cylinder 17 and the inwardly directed flange of sleeve 18 is hermetically sealed to the hollow cylinder 17 at a point near its upper end by means of a glass disk 19, similar to previously described disk 15. The grids 12 and 13 are conductively connected to and supported by a pair of metal rings or washers 20, 21 which are located between the outwardly directed flanges of the sleeves 14, 18, being insulated from each other by means of a ring 22 of suitable insulating material. The joint between the sleeves 14, 18 and the rings 20, 21 is hermetically sealed by means of a circular bead 24 of glass, constituted similar to the glass used for the disks 15, 19.

The composite cathode structure 11 is described and claimed in my copending application S. N. 522,097, filed February 12, 1944, and assigned to the assignee of the present invention. The structure 11 comprises a hollow metal tube 25, inwardly flanged at its upper end, and a tubular conductive member 26 of a thin metal foil, such as fernico, across the upper end of which is welded an emissive disk 27 constituted of a suitable electron emitting material, such as nickel coated with barium and strontium carbonates. A heating element or filament 28, disposed below the disk 27, has one of its terminals connected to the metal tube 25 and its other terminal conductively connected to and supported by a substantially rigid conductor 29 which passes through a glass disk 30 hermetically sealed across the lower end of tube 25. Surrounding the filament 28 is an eyelet or heat conducting member 31 welded to and supported from the flange portion of the fernico foil 26 and disk 27. In this composite structure, the fernico foil 26, welded to the upper flange of tube 25, serves thermally to isolate the emissive disk 27 from metal tube 25. The eyelet 31, constituted of a suitable heat conducting material such as nickel, serves to conduct to disk 27 any heat radiating outwardly from filament 28. Supported by and conductively connected to another substantially rigid conductor 33 sealed to the glass disk 30 is a getter 34 of suitable material. This getter is conductively connected at its opposite end to the conductor 29.

The evacuated chamber 2 comprises a removable envelope or bell jar 36 of glass or metal seated on a rubber member 37 vulcanized or otherwise bonded to the upper surface 38 of a table of suitable material, such as steel or aluminum. The table has a second metal plate or surface 40 spaced vertically below the surface 38 and connected therewith by means of an end wall 41 to define a duct for exhausting or evacuating the chamber defined by the bell jar 36. This duct is connected by means of a valve 42 to a large exhaust chamber or reservoir 43, which is evacuated by the vacuum pump 3, and serves as means rapidly to exhaust the bell jar 36, when the latter is connected to the exhaust chamber 43 by operation of the valve 42. Instead of being formed as a separate chamber, the reservoir 43 may comprise an extension pipe or conduit system.

The upper plate or surface 38 has an opening 45 centrally located below the bell jar 36. A plurality of vertical rods 46 secured to the upper surface 38 of the table serve to support a disk 47 of suitable insulating material to which is attached a plurality of spring clamps 48 for engaging the upper metal sleeve 14 of the electric discharge device 1. Disk 47 also carries a second

set of metal spring clamps 49 for engaging the lower metallic sleeve 18 of the discharge device. These clamps 48, 49 thus serve to support in a vertical position the upper portion of the electric discharge device comprising anode 10, metallic sleeves 18, 14, the grids 12, 13 sealed therebetween, and the lower metal tube 17.

The composite cathode structure 11 is supported within the sleeve 17 by means of the substantially rigid conductors 29, 33 clamped respectively to a pair of vertical rods 51, 52 by means of spring clamps 53, 54. At their lower ends, the rods 51, 52 are secured to a disk 55 of a suitable insulating material. An opening 56 in the lower wall 40 of the exhaust duct is sealed by means of a circular rubber gasket 57. At its perimeter, gasket 57 has a circular bead 58 which fits into corresponding grooves 59, 60 located, respectively, in the lower wall 40 and a metallic clamping ring 61 secured to this lower wall by any suitable means, such as screws (not shown). When the ring 61 is attached to the lower wall 40, the bead 58 is clamped in the grooves 59, 60 to prevent the seat thus formed. The gasket 57 has a relatively thick central portion 62 connected to the bead 58 by means of a thin flexible section 63.

A metal plate 64 lies over the upper portion of central section 62 of the gasket and another metal plate 65 is located below this central section of the gasket. These metal plates are clamped to this central portion of the gasket by means of a metallic rod 66 having a shoulder 67 engaging the lower surface of plate 65 and extending through aligned holes in plate 65, gasket 57, upper plate 64, and insulating disk 55. The upper plate 64 is spaced from the disk 55 by means of a metal collar 68. A nut 69 engaging threads at the upper end of rod 66, serves to clamp together the members 55, 64, 65. By this structure, the vertical rods 51, 52 and the composite cathode structure 11 supported thereby are clamped to the rubber sealing gasket 57, the thin section 63 of that gasket stretched across the opening 56 in the lower plate 49 serving as a flexible support for these rods.

In order to provide means to adjust the position of the composite cathode structure 11 within the metal tube 17, the member 65 has external threads engaged by an adjusting nut 71. A shoulder 72 on adjusting nut 71 abuts against the clamp 61 to serve as means for stretching the thin section 63 of the rubber gasket 57 and lowering or raising the composite cathode structure within the sleeve 17. The nut 71 may carry a scale 73 which cooperates with a proper marker on metallic member 65 so that the nut 71 serves as a micrometer arrangement for adjusting the vertical position of the cathode structure 11. The table 38, 40 may also be provided with suitable legs 75 to serve as supports therefor.

I also provide means for applying operating potentials to the electrodes of the device 1 while it is in position within the exhaust chamber 2. This means comprises the leads 76, 77, 78, 79 connected, respectively, to a spring clamp 80 which engages the anode 10, a spring clamp 81 which engages the metal sleeve 17 surrounding the cathode structure, the clamp 48 connected to the upper metal sleeve 14 and grid 12, and clamp 49 connected to the lower metallic sleeve 18 and grid 13. These leads may pass through the end wall 41 of the exhaust duct, an airtight seal between the side wall and the leads being maintained by a rubber disk 83 sealed across an open-

ing in wall 41. For purposes to be pointed out later, the lead 78, which contacts the anode 10, is connected to the positive terminal of a source of potential, such as the battery 84, through a resistance 85, the negative terminal of battery 84 being grounded. The lead 77, conductively joined to sleeve 17 surrounding the cathode structure, is connected directly to ground. Lead 78, connected to the screen grid 12 of the discharge device 1, is supplied with proper operating potential from a tap 87 on battery 84. Lead 79, connected to the control grid of discharge device 1, may be connected to ground through a bias battery 88 and, when required, a resistor 89.

Current for heating the filament 28 of the cathode structure may be supplied over a conductor 90 connected to the bottom of the vertical metal post 51 and insulatingly sealed at its point of passage through metal plates 64, 65 by means of rubber washers 91, 92 which may be formed integral with gasket 62. A conductor 94 similarly sealed at its point of passage through metal members 64, 65 is connected to the bottom point of the vertical metal post 52 and, in conjunction with lead 90, may serve to supply potential for flashing the getter 34.

In the manufacture of an electric discharge device of the type described, the anode 10 and the metal ferrule 14 are sealed in concentric relation by means of the glass disk 15. Similarly, the metal tube 17 and the ferrule 18 are sealed in concentric relation by means of the glass disk 19. Thereafter, the rings 20, 21 supporting the two grids and the ring of insulation 22 are clamped between the opposed outwardly directed flanges of the two ferrules and the glass bead 24 is hermetically sealed across these flanges. The cathode structure 11 is formed by welding the eyelet 31, the tube 26 of fernico foil, and the disk 27 together, after which the fernico foil is welded to the inwardly flanged upper end of the hollow metal tube 25 in which has been previously sealed the filament structure 28 and the getter 34, the glass disk 30 hermetically sealing the lower end of the hollow tube 25. The filament structure 28 is then supported from the vertical posts 51, 52 by clamping the substantially rigid conductors 29, 33 to these posts by means of spring clamps 53, 54. Thereafter, a ring 96 of solder is placed about the inwardly flanged upper end of the hollow tube 25. The unitary structure comprising the grid-anode assembly portion of the electric discharge device is then supported from the ring of insulating material 41, the sleeve 17 being slipped over the hollow metal tube 25 and spring clamps 48, 49 being adjusted to hold the grid-anode assembly in a vertical position. The bell jar 36 is placed over the assembly of the electric discharge device and its supporting structure so that the device may be evacuated.

As previously stated, the enclosed chamber 2 is connected to a large vacuum chamber 43, or any suitable reservoir, by means of a conduit defined by the metal plates 38, 40 and the side walls associated therewith. Preferably, the vacuum chamber 43 is considerably larger than the chamber 2 so that, when these chambers are connected together by operation of the valve 42, the pressure within the bell jar 36 is rapidly reduced to a very low value, such a system facilitating manufacture of the electronic tube to the extent that only a very short period of time is required to evacuate the device. While the discharge device is being evacuated, the filament 28 is heated by means of current supplied thereto over the

conductor 90 and conductor 77 and spring contact 81, the connection between the filament and the sleeve 17 being made through the ring of solder and the metallic contact between sleeves 17 and 25. Preferably, the current supplied to the filament is larger than that used in normal operation of the electric discharge device and is of sufficient value effectively to sinter the cathode or emissive disk 27 and to degas the electrodes of the discharge device. Due to the fact that this degassing takes place within the evacuated bell jar 36, substantially no gas ions are present in the discharge device and a high voltage of the order of twice the normal voltage may be impressed across the filament with no fear of producing arcing and injuring the filament or electrodes. By this means, therefore, more effective and more rapid degassing of the electrodes is permitted. At the same time, the high temperatures thus produced may be used to melt the ring of solder 96 causing it to flow between sleeves 17 and 25 and hermetically seal the region within the discharge device from the evacuated region within bell jar 36.

Operating potentials may be supplied also to the anode, cathode, and grids of the device through the previously described electrical connections made over conductors 76-79 and clamps 48, 49, 80 and 81.

After the pressure within the enclosed region 2 has been reduced to a low value, for example of the order of 10 microns, by means of the vacuum chamber 43 and the vacuum pump 3, the ring of solder 96, if not already melted by the heat produced by the excess currents in filament 28, is melted by means of high frequency currents supplied thereto inductively from a coil 98 connected to any suitable source (not shown) of high frequency currents. The melted solder 96 forms a molten metallic seal between the two sleeves 17, 25, sealing the region within the electric discharge device from the region within the bell jar 36. To this end, the sleeves 17 and 25, as well as other metallic parts of the electric discharge device, preferably are made of a material to which molten solder easily adheres, such a material being, for example, silver-plated steel, a suitable solder being used to form the ring of solder 96.

When the inner region of the device has been thus sealed from the remainder of the evacuated chamber, if additional time is required to degas or remove occluded gases from the electrodes, the molten solder may be allowed to cool. The tube is removed from the bell jar to continue the degassing operation according to the method normally used in manufacturing such tubes and thereafter is replaced in the bell jar and the latter exhausted. If all occluded gases have been removed by the time the tube and bell jar are exhausted and the ring of solder 96 is melted, suitable potentials may be impressed across the leads 90, 94 to flash the getter material 34. A small hole or orifice 97 in the upper end of the metal sleeve 25 provides communication between the interior of the composite cathode 11 and the region between the electrodes of the electric discharge device so that the getter 34, after vaporization, may further reduce the gas pressure within the device to a value, for example, of the order of .01 micron, creating a final vacuum condition within the device. The surface tension of the molten seal of solder between the sleeves 17, 25 maintains the differential pressures between the inner and outer surfaces of the electric discharge

device and prevents contamination of the interior thereof by gases on the outside and within the chamber 2.

In order to permit the manufacture of an electric discharge device having predetermined characteristics, either physical or electrical, the molten metallic seal between the sleeves 17, 25 provides means whereby the spacing of the emissive surface 27 from the anode 10 or the electrode 13 may be adjusted either to a desired physical value or to a distance which gives a desired electrical characteristic to the electric discharge device. In the case of tubes which have been removed from the bell jar for completion of the degassing operation, the tube is replaced in the chamber 2 and the solder seal remelted prior to the electrode spacing operation. For tubes which do not require additional time for degassing, the tube is allowed to cool to normal operating temperature and the electrodes are spaced without removing the tube from the evacuated bell jar. Where a particular spacing between electrodes is desired, such a spacing is obtained by adjustment of the micrometer screw 71 until the cathode 27 contacts the grid 13. It is apparent that due to the differential pressures on the opposite sides of the thin section 63 of the rubber gasket 57, this gasket is flexed inwardly toward the bell jar, tending to raise the position of the cathode within the sleeve 17. Such inward movement of the cathode supporting structure is limited by shoulder 72 on the micrometer screw 71. Contact of the emissive disk 27 with the grid 13 may be indicated by a suitable instrument used to show a current flow between these electrodes when direct electrical connection is made. Thereafter, the micrometer screw 71 is adjusted to lower the disk 27 exactly to the desired distance below the grid 13, the scale 73 indicating this distance. By such means, very small distances and very close spacing of electrodes may be obtained in an electric discharge device, distances for example of the order of .001 inch or less. Moreover, since the physical spacing is made with the tube elements heated to operating temperatures, assurance is had that such a spacing is obtained when the tube is used subsequently.

When it is desired to manufacture an electric discharge device having particular electrical characteristics, for example a particular grid voltage-plate current characteristic, the electrical connection shown in Fig. 1 of the drawing may be used. An ammeter 99 connected in series between the cathode and ground indicates the plate current of the discharge device. By adjusting the spacing of the electrodes by means of the micrometer screw 71, the position of the cathode with respect to the anode and control electrodes may be varied until a proper plate current reading is obtained. In this way, any errors due to previous inaccuracies in assembly may be compensated and all tubes manufactured may be given substantially identical characteristics.

In Fig. 2, there is shown an alternative circuit which may be used in spacing the electrodes of a discharge device manufactured in accordance with my invention. In the circuit of Fig. 2, the discharge device 1 is represented diagrammatically, with the leads 76-79 being connected to the same electrodes as shown in the circuit of Fig. 1. A source of high frequency oscillations 100 is connected across an inductance 101 through an ammeter 102. The leads 76-79 may be connected in any desired arrangement to connect the cathode any any other electrode as a capacitance in parallel with the inductance 101, the lead 77 from

the cathode being connected to one terminal of the inductance 101 and the lead associated with the selected electrode being connected to the opposite terminal of this inductance. By varying the position of the composite cathode structure 11 within the tube 17, the capacitance connected in parallel with the inductance 101 may be varied to tune this inductance to a resonance condition at the frequency of the source 100, such a condition being indicated by a minimum current reading on ammeter 102. This method of adjusting the position of the electrodes is of value, especially where a desired value of interelectrode capacitance is desired for electronic tubes of special characteristics.

From the foregoing, it is seen that my invention provides an improved technique for manufacturing electric discharge devices, by means of which tubes having closely spaced electrodes may be manufactured, the spacing being adjusted to a desired value while the tube is being exhausted in an evacuated chamber. Also, tubes having nearly identical characteristics may be constructed since the grid-to-cathode spacing may be adjusted to compensate for small errors in the spacing of the other electrodes. While I have described the method and apparatus as being employed in the manufacture of a tube of the tetrode type, it is apparent that they may be employed to manufacture diodes, triodes, or tubes having any other desired combination of electrodes. Likewise, although I have illustrated and described a particular type of electric discharge device, namely, one in which the anode of the device extends in a direction opposite to the cathode and is supported by the metallic sleeves 14, 18 which serve as external connections for the grids, it is apparent that my method and apparatus may be employed to manufacture any type of discharge device in which a pair of electrodes are to be spaced, the adjustable electrode extending through a metallic sleeve to which it is subsequently soldered. Thus, a glass envelope may be employed and external connections to the electrodes may extend from the bottom of the device according to the usual technique.

Furthermore, in certain of the above descriptive matter and in the accompanying claims where the terms "characteristic," "characteristics," or "dimension" are used, it is understood that these terms are used in the sense of electrical characteristics or physical characteristics of a predeterminable nature, that is, which are determined through measurements, electrical or physical, during the manufacture of the device, the physical characteristics or dimensions excluding the gas pressure within the electric discharge device being manufactured.

While I have shown and described my invention as applied to particular systems embodying various devices diagrammatically shown, it will be obvious to those skilled in the art that changes and modifications may be made without departing from my invention and I, therefore, aim in the appended claims to cover all such changes and modifications as fall within the true spirit and scope of my invention.

What I claim as new and desire to secure by Letters Patent of the United States is:

1. The method of manufacturing an electric discharge device which includes exhausting said device and positioning one electrode thereof to establish a predetermined characteristic of said device during said exhausting.
2. The method of manufacturing an electric

discharge device which includes exhausting said device and adjusting the electrical characteristics of said device by moving an electrode thereof after said device is exhausted.

3. The method of manufacturing an electric discharge device which includes exhausting said device and adjusting the grid voltage-plate current characteristic of said device during the exhausting thereof.

4. The method of manufacturing an electric discharge device which includes exhausting said device and adjusting the grid voltage-plate current characteristic of said device at normal operating temperatures during the exhausting thereof.

5. The method of manufacturing an electric discharge device which includes exhausting said device and adjusting the spacing between a pair of the electrodes thereof during the period of exhausting the device.

6. The method of manufacturing an electric discharge device which includes heating said device to normal operating temperatures and adjusting the spacing between a pair of the electrodes thereof at said temperatures.

7. The method of manufacturing an electric discharge device which includes heating the electrodes thereof to normal operating temperatures and adjusting the spacing between a pair of said electrodes during the exhausting of said device and at said temperatures.

8. The method of manufacturing an electric discharge device which includes applying operating potentials across the electrodes of said device during the exhausting thereof and adjusting the spacing between a pair of said electrodes with said potentials thereacross and during said exhausting.

9. The method of manufacturing an electric discharge device which includes supporting said device within an evacuated chamber, supplying operating potentials across the electrodes of said device, and adjusting the spacing between a pair of said electrodes with the potentials thereacross and while said device is in said chamber.

10. The method of manufacturing an electric discharge device which includes exhausting said device, heating the electrodes thereof to abnormal temperatures, cooling said electrodes to normal operating temperatures, and then adjusting the spacing between a pair of said electrodes at said normal operating temperatures.

11. The method of manufacturing an electric discharge device of the type having an envelope with an aperture and an electrode stem which projects through said aperture which includes forming a ring of molten metal about said electrode stem to establish a vacuum seal for said device and sliding said stem through the ring of molten metal to adjust the position of said electrode within said device.

12. The method of manufacturing an electric discharge device of the type having an entrance through which the device may be evacuated which comprises evacuating said device, establishing a molten metallic seal over said entrance, and then adjusting the position of an electrode within said device through said seal.

13. The method of adjusting the spacing of an electrode within an evacuated vessel, said electrode having a stem portion projecting through a wall of said vessel which comprises forming a molten metal seal about said stem, sliding said stem through said seal to a desired position, and

allowing said molten metal to harden to fix said position.

14. The method of manufacturing an electric discharge device having an entrance through which the device may be evacuated comprising establishing a primary vacuum within said device, using molten metal to seal said entrance, reducing still further the gas pressure within said device, and thereafter adjusting the position of an electrode in said device.

15. The method of manufacturing an electric discharge device which includes connecting a reactive circuit across a pair of the electrodes of said device, exhausting said device, and adjusting the spacing of said electrodes to tune said circuit to resonance during said exhausting.

16. The method of manufacturing an electric discharge device of the type having an anode, a control electrode, and a cathode in spaced relation, which comprises establishing said electrodes in proximate positions, exhausting said device, and spacing said electrodes to a final position while said device is being exhausted.

17. The method of manufacturing an electric discharge device of the enclosed type and having a substantially cylindrical cathode structure closely surrounded by a metallic sleeve which comprises placing a ring of solder about said cylindrical cathode, supporting said device within a closed chamber, evacuating said device and said chamber, and melting said solder hermetically to seal the space between said sleeve and said cathode.

18. The method of manufacturing an electric discharge device of the enclosed type and having a substantially cylindrical cathode structure closely surrounded by a metallic sleeve which comprises placing a ring of solder about said cylindrical cathode, supporting said device within a closed chamber, evacuating said device and said chamber, heating said cathode to abnormal temperatures to melt said solder hermetically to seal the space between said sleeve and said cathode, and adjusting the position of said cathode structure within said device while said solder is in a molten condition and said device is supported within said evacuated chamber.

19. The method of manufacturing an electric discharge device of the type having a cylindrical anode and a cylindrical cathode in alignment, said cathode being surrounded by a cylindrical tube, which comprises insulatingly sealing said tube to said anode and in concentric alignment therewith, inserting said cathode within said tube, exhausting the space within said device, establishing a seal of molten metal between said tube and said cathode, adjusting the spacing between said cathode and said anode during said exhausting of said device, and thereafter cooling said molten metal mechanically to connect said tube and said cathode.

20. The method of manufacturing an electric discharge device of the type having a cylindrical anode and a cylindrical cathode in alignment, said cathode being surrounded by a cylindrical tube, which comprises insulatingly sealing said tube to said anode and in concentric alignment therewith, inserting said cathode within said tube, establishing a vacuum within said device and in a region external to said device, forming a seal of molten metal between said tube and said cathode, heating the electrodes of said device to normal operating temperatures, applying operating potentials between said electrodes, and adjusting the spacing between said electrodes to obtain a

desired electrical characteristic of said device, said spacing being accomplished while the vacuum of said region is maintained.

21. In combination, a closed chamber, means for exhausting said chamber, means for supporting an electric discharge device within said chamber, and means accessible from the exterior of said chamber for varying the spacing between a pair of the electrodes of said device within said chamber.

22. In combination, a closed chamber, means for establishing a vacuum within said chamber, means within said chamber for supporting an electric discharge device to be evacuated, means for hermetically sealing said device after evacuation without removing said device from said chamber, and means accessible from the exterior of said chamber for adjusting the position of an electrode of said device after said device has been hermetically sealed.

23. Apparatus for manufacturing an electric discharge device comprising an exhaust chamber, an exhaust reservoir having a large volume relative to the volume of said chamber, means for supporting said device within said small chamber, valve means for connecting said chamber to said reservoir to effect rapid exhausting of said device upon operation of said valve means, and means for adjusting the position of an electrode of said device without removing said device from said chamber.

24. In combination, a vessel adapted to be evacuated having a flexible wall, means adapted to support an electron discharge device in fixed position in said vessel, means connecting an electrode within said discharge device for mechanical movement with said wall, and micrometer means for moving said wall to position said electrode within said device without disturbing the vacuum condition within said vessel.

25. Apparatus for manufacturing an electric discharge device comprising a closed chamber, means for exhausting said chamber, means for supporting said device within said chamber, means for heating said device within said chamber to normal operating temperatures, and means for spacing a pair of electrodes of said device at said temperatures and without removing said device from said chamber.

26. In combination, a closed chamber, means for supporting an electric discharge device to be evacuated within said chamber, means for supplying operating potentials to the electrodes of said device, means for evacuating said chamber to establish a desired gas pressure within said device, and means for adjusting the relative position of said electrodes to obtain a desired electrical characteristic of said device without removing said device from said evacuated chamber.

27. Apparatus for manufacturing an electric discharge device comprising a closed chamber, means for supporting said device within said chamber, means for evacuating said chamber, means for hermetically sealing said device while said device is within said chamber, and means for moving an electrode within said device after said sealing thereof.

28. Apparatus for manufacturing an electric discharge device of the type having an anode, a grid, and a cathode in spaced alignment and including a metallic sleeve surrounding a portion of said cathode and formed as a unitary structure with said anode comprising, a closed chamber, means for supporting said unitary structure within said chamber, additional means for sup-

porting said cathode within said sleeve, means for evacuating said chamber to establish a desired gas pressure within said device, means for forming a molten metallic seal between said sleeve and said cathode, and means external of said chamber for adjusting the spacing of said cathode and said grid without removing said device from said chamber.

29. Apparatus for manufacturing an electric discharge device of the type having an anode, a grid, and a cathode in spaced alignment and including a metallic sleeve surrounding a portion of said cathode and formed as a unitary structure with said anode comprising, a closed chamber, means for supporting said unitary structure within said chamber, additional means for supporting said cathode within said sleeve, means for evacuating said chamber to establish a desired gas pressure within said device, means for forming a molten metallic seal between said sleeve and said cathode, means for supplying operating potentials to the electrodes of said device within said chamber, and means for adjusting the position of said cathode within said sleeve to obtain a desired electrical characteristic of said device.

30. In combination, a closed chamber, an electric discharge device to be evacuated supported within said chamber, means for evacuating said chamber to establish a low gas pressure within said device, means for hermetically sealing said device, and means for adjusting the electric characteristics of said device after said device has been hermetically sealed and while said device is in said evacuated chamber.

31. Apparatus for manufacturing an electric discharge device having a pair of electrodes, said apparatus comprising a closed chamber, means for supporting a discharge device in said chamber, means for evacuating said chamber, means for supplying operating potentials to the electrodes of a device supported in said chamber, and means for effecting relative movement of the electrodes while the device is in said evacuated chamber.

32. The method of manufacturing an electric discharge device which comprises supporting said device within a closed chamber, evacuating said chamber and said device, using a molten metal to seal said device, allowing said seal to harden, removing said device from said chamber and degasifying said device, supporting said device in an evacuated chamber and melting said seal, and adjusting the position of an electrode of said device while said device is in said evacuated chamber.

33. Apparatus for manufacturing an electric discharge device including an anode and cathode in spaced relation, said apparatus comprising a chamber to be evacuated, means for supporting a discharge device within said chamber, means for hermetically sealing a discharge device supported within said chamber, means for evacuating said chamber and the device, and means accessible from the exterior of said chamber for adjusting the relative position of said anode and cathode without disturbing the vacuum condition within said chamber.

34. Apparatus for manufacturing an electric discharge device including a plurality of electrodes, said apparatus comprising a chamber, means for supporting a discharge device within said chamber, means for evacuating said chamber to establish a low gas pressure with a device supported in said chamber, means for establish-

ing a seal to hermetically seal the envelope of a device in said chamber and means for effecting relative movement of said electrodes to determine a characteristic of the device without disturbing the vacuum condition within the device.

JAMES E. BEGGS.
